UNITED STATES PATENT OFFICE

2,616,614

THERMOCOMPRESSOR

John F. Plummer, Jr., Phillipsburg, N. J., assignor
to Ingersoll-Rand Company, New York, N. Y.,
a corporation of New Jersey

Application March 18, 1948, Serial No. 15,682

2 Claims. (Cl. 230—95)

1

This invention relates to thermo-compressors, and more particularly to steam ejectors of the type which are normally used as the first stage, or first and second stages, of a thermo-compressor comprising a plurality of steam ejectors connected in series, i. e. with each ejector discharging into the succeeding ejector.

In this arrangement at least the first stage ejector will operate at or below the freezing pressure of water and, therefore, any moisture entrained in the propelling steam will freeze and tend to collect on the surface of the inlet end portion of the diffusor.

Heretofore, in order to prevent the formation of such ice in the diffusor of an ejector, it has been the practice to warm the diffusor with a steam or electrical coil. This means, of course, that an auxiliary or supplementary source of heat is necessary for the efficient operation of the ejector.

In the present invention, the formation of ice in the diffusor is prevented by utilizing an inherent operating characteristic of the ejector. Specifically, the fluid flowing through the diffusor of an ejector is subject to a temperature rise due to the change in pressure of such fluid. Thus, by utilizing the heat available in fluid discharged from the diffusor to warm the inlet end portion of said diffusor, it is readily apparent that the ejector will operate efficiently at or below the freezing pressure of water.

It is accordingly one object of my invention to warm the diffusor of an ejector with the fluid discharged from the diffusor.

A second object is to convey fluid from the discharge end of a diffusor into contact with the outer surface of the inlet end portion of the diffusor.

Other objects will be in part obvious and in part pointed out hereinafter.

In the drawings accompanying this specification and in which similar reference numerals refer to similar parts,

Figure 1 is a longitudinal view, in section, of an ejector constructed in accordance with the practice of the invention, and

Figure 2 is a longitudinal view, partly in section, of an ejector embodying an alternate construction of the present invention.

Referring to the drawings and more particularly to Figure 1, 10 designates, in general, a steam ejector of the conventional type having a nozzle 11 mounted on the ejector casing 12 adjacent the inlet 13 for the fluid to be evacuated. Adapted to the inlet 13 is a diffusor 14 which is,

5 in this instance, of the converging-diverging type with the converging or inlet end portion 15 in communication with the inlet 13 and the diverging portion 16 serving as an outlet for the fluid to be evacuated and the energizing fluid.

10 Encircling the diffusor 14 and spaced therefrom is a housing 17 which forms a fluid containing chamber 18 to receive the discharge from the diffusor 14. An opening 19 is provided for the housing 17 at the inlet end of the diffusor so that fluid discharged from the diffusor is brought into intimate contact with the outer surface of the diffusor before it escapes from the chamber 18. In this manner all parts of the diffusor are 15 maintained at a temperature above 32° F., thereby preventing ice particles from adhering to the surface thereof.

An alternate construction of the present invention is shown in Figure 2 in which only the converging or inlet end portion 15 of the diffusor is 20 warmed by the ejector discharge. In this instance a conventional ejector 20 is provided with an extension 21 which conveys discharge fluid from the outlet end 16 of the ejector into intimate contact with the outer surface of the inlet end portion of the diffusor 14. To this end, the portion of the extension 21 which is adapted to receive the fluid as it is discharged from the diffusor, is U-shaped and the intermediate portion of the extension is substantially parallel to the diffusor, whereas the discharge end portion 25 22 of the extension 21 forms a steam jacket 23 for the inlet end or converging portion 15 of the diffusor 14.

30 In order to reduce the radiant heat loss of the fluid flowing through the ejector, the extension 21 in this instance and the housing 17 in the first case, are encased by an insulating material 24, thus maximizing the amount of heat available 35 in the discharge fluid to warm the diffusor.

35 It is now obvious from the previous discussion that the present invention provides an ejector which is simple in construction and capable of efficient operation under icing conditions without 40 the aid of an auxiliary or supplementary source of heat.

I claim:

1. A steam ejector adapted to operate at or 45 below the freezing pressure of water comprising 50 a casing having an inlet and a diffusor, a nozzle for introducing propelling steam into said casing, a closed housing entirely enclosing said diffusor throughout its length and extending beyond the discharge end of the diffusor and spaced 55 therefrom to form a chamber between the hous-

ing and diffusor to receive the discharge of the ejector, and a discharge opening for said housing.

2. In a thermo-compressor, a casing having an inlet and a diffusor arranged to define a continuous passage through the compressor for the fluid to be pumped, a nozzle in the inlet for directing propelling fluid into the diffusor, a housing the downstream end portion of which encases the upstream end portion of the diffusor to form a chamber therearound, the upstream end of the housing being of at least the same diameter and coaxial with the downstream end of the diffusor to receive the entire discharge of the diffusor and conduct such discharge to said chamber, and an outlet for the housing at the downstream end portion thereof.

JOHN F. PLUMMER, JR.
